(57) **CLAIM**

The ornamental design for display device, as shown and described.

DESCRIPTION

FIG. 1 is a perspective view of a display device according to an embodiment of the present design in a folded state;

FIG. 2 is a front view thereof;

FIG. 3 is a rear view thereof;

FIG. 4 is a left side view thereof;

FIG. 5 is a right side view thereof;

FIG. 6 is a top view thereof, with the bottom view being a mirror image thereof;

FIG. 7 is another perspective view thereof;

FIG. 8 is a perspective view thereof in an unfolded state;

FIG. 9 is a front view thereof;

FIG. 10 is a rear view thereof;

FIG. 11 is a left side view thereof, with the right side view being a mirror image thereof;

FIG. 12 is a top view thereof, with the bottom view being a mirror image thereof;

FIG. 13 is another perspective view thereof;

FIG. 14 is another perspective view of the display device in a folded state and showing environment; and,

FIG. 15 is another perspective view of the display device in an unfolded state and showing environment.

The broken lines immediately adjacent the shaded areas represent the bounds of the claimed design while all other broken lines are directed to environment and are for illustrative purposes only; the broken lines form no part of the claimed design.
